United States Patent Office.

JAMES M. RAGSDALE, OF MCCOY'S STATION, INDIANA.

Letters Patent No. 83,547, dated October 27, 1868.

IMPROVED ROAD-GRADER.

The Schedule referred to in these Letters Patent and making part of the same.

To all whom it may concern:

Be it known that I, JAMES M. RAGSDALE, of McCoy's Station, in the county of Decatur, and in the State of Indiana, have invented certain new and useful Improvements in Road-Graders; and do hereby declare that the following is a full, clear, and exact description thereof, reference being had to the accompanying drawings, and to the letters of reference marked thereon.

In the annexed drawings, making part of this specification, A represents a frame, which is made in a durable manner, and provided with the two short axles B and B', one of which, B, revolves, while the other is stationary in this respect.

The axle B is hinged to the frame, near its centre, and the outer end of said axle, upon which the wheel J is secured, is free, so that it can play vertically, when necessary. A lever, k, is connected at one end to the frame A, by means of the uprights M, and is connected to the axle B by means of a standard, L. The object of this lever is to raise or lower that end of the frame next to the wheel J. Close to the wheel J, and to the under side of the frame A, is secured a plow, E, and consequently, when this end of the frame is raised or lowered, the plow is also, and its depth in the ground is thus regulated.

Standing vertically, and at the centre of the frame, is a shaft, C, which extends both below and above said frame. Upon the upper end of this shaft is secured a gear-wheel, D, and upon the lower end is secured a large plate-wheel, E, the periphery of which reaches close to the plow R, so as to receive the earth upon it, which the mould-board of the plow turns over. The wheel D gears into an idle-wheel, F, and also into a

bevel-wheel, S. The bevel-wheel S is secured upon the inner end of the revolving axle B', and serves to communicate motion from the driving-wheel I to the gear-wheel D.

The idle-wheel F gears into a pinion, G, which is secured to the upper end of a vertical shaft, G'.

Upon the lower end of the shaft G', is secured a series of curved arms, H H. These arms play, when the shaft G' revolves, immediately over the wheel E, so as to throw off the earth, which is received upon said wheel from the plow R.

In using this machine, when it is drawn forward, the plow loosens up the earth, and throws it upon the revolving plate-wheel E. This wheel carries it around, until it reaches the arms H H; and these arms revolving, remove the earth from said wheel, and throw it to one side of the machine.

Having thus fully described my invention,

What I claim as new, and desire to secure by Letters Patent, is—

1. The arrangement of the wheel E, plow R, and revolving arms H H, when connected with the frame A, and constructed and operating substantially as specified.

2. The combination of the hinged axle B' and lever K, with the frame A, provided with the wheel E, plow R, and arms H H, and connected to operate as set forth.

In testimony that I claim the foregoing, I have hereunto set my hand, this 16th day of March, 1868.

JAMES M. RAGSDALE.
